(57) **CLAIM**

We claim the ornamental design for an induction range, as shown and described.

DESCRIPTION

FIG. 1 is a front perspective view of a first embodiment of an induction range showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is an enlarged view of the encircled portion in FIG. 4;
FIG. 9 is a front perspective view of the induction range in a state of use;
FIG. 10 is an exploded view thereof showing the induction range in a state of use;
FIG. 11 is a front perspective view of a second embodiment of the induction range showing our new design;
FIG. 12 is a front view thereof;
FIG. 13 is a rear view thereof;
FIG. 14 is a left-side view thereof;
FIG. 15 is a right-side view thereof;
FIG. 16 is a top view thereof;

(Continued)

FIG. 17 is a bottom view thereof; and, FIG. 18 is an enlarged view of the encircled portion in FIG. 14.

The broken lines in the drawings depict portions of the induction range that form no part of the claimed design. The dot-dashed broken lines encircling portions of the claimed design that are shown in enlargements form no part of the claimed design.

1 Claim, 14 Drawing Sheets
